UNITED STATES PATENT OFFICE.

JOHN F. MARTENS, OF CINCINNATI, OHIO, ASSIGNOR TO REDWAY & BURTON, OF SAME PLACE.

DESIGN FOR A COOKING-STOVE.

SPECIFICATION forming part of Design No. 16,665, dated April 27, 1886.

Application filed March 15, 1886. Serial No. 195,359. Term of patent 3½ years.

To all whom it may concern:

Be it known that I, JOHN F. MARTENS, a citizen of the United States, and a resident of the city of Cincinnati, in the county of Hamilton and State of Ohio, have invented and produced a new and original Design for Cook-Stoves, of which the following is a clear, full, and exact description, reference being had to the accompanying illustrations, forming part thereof.

In the illustrations, Figure 1 shows a cook-stove having all the features of my design with the heating-closet and reservoir attached. Fig. 2 shows the principal features of my design with the heating attachment and reservoir removed.

The general configuration and ornamentation of the stove are shown in Figs. 1 and 2.

The relative proportions and configurations 20 of the fire-door and of the oven-door are shown; also the position and configuration of the feed-door and hearth.

The oven-door is ornamented with a novel and peculiar figure representing a series of 25 twigs extending from one stem, which stem extends from the lower forward corner backward and upward across said door. On the upper termination of said stem, near the upper rear corner of said door, is the flower A, 30 and from a twig of said stem is another flower, B, near the lower rear corner of said door; also, from said twig is another flower near the center of the door. This oven-door is also ornamented with band C, extending across its forward face, and centrally located in this band is the handle of the door. On this oven-door, at the rear end, midway its height, is a butterfly; but the leading feature of design is the peculiar stem, twigs, and flowers, and the 35 band. On the fire-door is a smaller stem hav-

ing two twigs emanating from said stem and extending at a line almost at right angles to the stem, and terminating, respectively, in flowers D and E.

The feed-door F is provided with a design 45 consisting of two bands extending vertically across its face and a twig and flowers between said bands, as shown.

The front of the stove, underneath the hearth, is provided with an ornamental panel, 50 G, ornamented somewhat similar to the feed-door F, by two bands and twig, with flowers between said bands, as shown.

The leading features of my design are the ornamentation on the oven-door, as described 55 and shown; the ornamentation on the fire-door, as described and shown; the ornamentation on the feed-door, as described, and the ornamentation on the front panel underneath the hearth, as described and shown. 60

What I claim as new and of my invention, and desire to secure by Letters Patent, is—

1. In a design for a stove, the oven-door having the ornamentation or parts A, B, and C, as described and shown. 65

2. In a design for a stove, the fire-door having the ornamentation of a stem dividing into twigs which terminate in the flowers D and E, as described and shown.

3. In a design for a stove, the ornamentation of the panel underneath the hearth with bands and sprigs, as described and shown. 70

4. The design for a cooking-stove, consisting in the ornamentation of the oven-door, the fire-door, the feed-door, and the panel beneath 75 the hearth, as described and shown.

JOHN F. MARTENS.
